(57) **CLAIM**

I claim the ornamental design for a bottle basket of a decanting cradle, as shown and described.

DESCRIPTION

FIG. 1 is a perspective top, rear and left side view of a bottle basket of a decanting cradle showing my new design; FIG. 2 is a left side elevational view thereof, the right side being a mirror image;

FIG. 3 is a front elevational view thereof;

FIG. 4 is a rear elevational view thereof;

FIG. 5 is a top plan view thereof; and,

FIG. 6 is a bottom plan view thereof.

The base portion of the decanting cradle is shown in broken lines for environmental purposes only and forms no part of the claimed design.
